VOTING MACHINE

Ransom F. Shoup, Ardmore, Pa., assignor to The
Shoup Voting Machine Corporation, Philadel-
phia, Pa., a corporation of Delaware

Application September 13, 1940, Serial No. 356,595

15 Claims. (Cl. 235—55)

This invention relates to voting machines and more especially to voting machines of the type illustrated in Shoup et al. Patent No. 2,054,102, and Shoup application Serial No. 260,283 of which this application is a continuation in part.

In the machine of the Shoup et al. patent, there are provided personal choice slots and closing slides therefor. At a general election a voter may register his choice for any office by moving the appropriate slide and writing in the name of his choice on the paper strip provided for that purpose.

Shoup application, Serial No. 260,283 discloses means for conditioning the machine of the Shoup et al. patent for election of delegates to national conventions of the various political parties. When the machine is conditioned for the election of delegates, a group of voting spindles is allocated to each party and a voter can actuate only a predetermined number of spindles in the group allocated to his party, the number being determined by the number of delegates to be elected by his party and each party usually having a different number of delegates to elect than any other party. The delegate mechanism of said Shoup application is of such construction and arrangement that in some instances it releases a number of personal choice slides from the control of the spindle interlock, depending upon the difference between the numbers of delegates to be elected by the various political parties, thus making it possible in the absence of prevention means for a voter to vote for the full number of delegates to which his party is entitled by actuation of a corresponding number of voting spindles and then in addition to write in an additional number of choices on the personal choice paper strip.

An object of this invention is the provision of means co-operative with the delegate mechanism to limit the total number of choices that can be registered by any voter to the number of delegates to which his party is entitled, while being effective to control the personal choice slides in the normal manner for general voting.

Other objects, novel features and advantages of this invention will become apparent from the following specification and accompanying drawings, wherein:

Fig. 1 is a fragmentary horizontal section of a voting machine embodying the invention;

Fig. 2 is a section substantially on the line 2—2 of Fig. 1;

Fig. 3 is a section on the line 3—3 of Fig. 1; 55

Figs. 4, 5, and 6 are sections respectively on the lines 4—4, 5—5 and 6—6 of Fig. 3;

Figs. 7, 8 and 9 are perspective views of parts of the machine;

5 Fig. 10 is a view similar to Fig. 4 with the part shown in Fig. 9 attached;

Fig. 11 is a fragmentary view similar to Fig. 1 of a modification;

Fig. 12 is a section on the line 12—12 of Fig. 11;

10 Figs. 13 and 14 are sections on the lines 13—13 and 14—14 respectively of Fig. 12, and

Figs. 15, 16 and 17 are perspective views of parts of the modification.

In this paragraph is described structure common both to voting machines embodying the present invention and to the machine of Shoup, et al. Patent No. 2,054,102, and corresponding parts are designated by the same reference characters in so far as is practical. In Fig. 1 is disclosed a spindle locking and restoring frame consisting of horizontal bars 65 connected by vertical channel bars 66 having cut-out portions providing rungs 67 arranged to engage arms 59 carried by the voting spindles 38 having handles 30. The bars 65 are provided with oblique slots in which voting spindles are received and also with an interconnecting track member 65b which engages rollers 65a carried by a vertical bar 68. The bar 63 is provided with oblique slots through which 15 extend pins 69 carried by the casing. At the lower end of the bar 68 is provided a stud 70 which extends into the slot 58a in the main cam bar 58 (Fig. 2). The arrangement is such that upon leftward movement of the main cam bar 58 from its curtain-open position (Fig. 2) to its curtain-closed position (not shown) the bar 68 is elevated and moved to the left from the position shown in Fig. 1 and upon return movement of the main cam bar to its curtain open position

roller 143 to a take-up roller (not shown), Fig. 1. A yoke 153 pivotally supported on a rod 158a is rotated counter-clockwise from the position shown in Fig. 1 by movement of any closure 149 to open position through the medium of a slide 223 subsequently to be described and if actuated is returned to its original position upon return of the machine to curtain-open position by means, not shown. The yoke 150 coacts with mechanism, not shown, to advance the strip 142 a predetermined distance for each actuation of the yoke. A vertical plate 159c of the shape shown in Fig. 1 is provided with a vertical series of apertures constituting guideways for links 161 which, at one end, are attached to arms 160 pivotally supported by the rod 158a mounted in brackets 159b attached to the plate 159c, and each link 161 is provided with a pin 61a connected to an interlock strap 61. Means actuated by each personal choice slot closure engages each corresponding arm 160 to move the latter leftward upon actuation of the closure, thereby actuating a corresponding interlock strap 61 of the spindle interlock. Means, later to be described, and equivalent to the means shown in said Patent No. 2,054,102 are provided for returning any actuated arm to the position shown in Fig. 1 upon return of the machine to curtain-open position. The operation of the above-described mechanism is the same as in said Shoup, et al. patent and will not be herein set forth in detail.

A plate-like carrier 231 (Figs. 1 and 2) bears against the rear face of the bar 68 and is provided with horizontal slots through which extend the pins 69 fixed to the casing and also with horizontal slots 292. The carrier 231 is also provided with vertical slots through which extend pins carried by the bar 68 and supporting the rollers 65a. The carrier 231 is limited to horizontal movement by the pins 69 and moves leftward from the position shown in Fig. 2 upon upward and leftward movement of the bar 68. Three vertical plates 293, 294 and 295 have corresponding oblique slots extending downwardly from left to right through which extend pins 296 also extending through the slots 292 in the carrier 231. The pins 296 are provided with heads 297 engaging the outer surface of the plate 295 and carry washers 298, 299, 210 and 210a, the latter of which have hubs over which the ends of the pins are spread to prevent withdrawal of the pins (Fig. 1). The upper ends of the oblique slots previously referred to normally contact the pins 296 to support the plates from the carrier. The slot 292 is of less length than the extent of horizontal movement of the bar 68 to which the carrier 231 is attached, such extent of movement being determined by operating requirements of the voting machine other than those to which this invention is directed. Therefore, a lost motion connection exists between the pins 296 and the carrier 231 so that upon horizontal reciprocation of the carrier the pins are also horizontally reciprocated but over a shorter path. In curtain open position, the pins 296 contact the left ends of the slots 292 and in curtain closed position these pins contact the right ends of said slots. A stop 211 is provided on the plate 159c for engagement by the right edges of the plates 293, 294 and 295 and a stop 211a is carried by the casing 19 for engagement by the hub of the washer 210a to limit leftward movement thereof from the position shown in Fig. 1. The plates 294 and 295 are of the same width while the plate 293 is slightly wider than the

other two plates and are staggered with respect to the plate 293 in such relation that at no time does the left edge of either of the plates 294 and 295 extend beyond the left edge of the plate 293. 5 Pins 293a, 294a and 295a are carried by the plates 293, 294 and 295 respectively, these pins being arranged at different elevations (Fig. 2). The pin 293a projects through an aperture in the carrier 231 of proper area to permit the later-to-be-described movement of the pin 293a. The pin 294a extends through apertures in the bar 293 and the carrier 231 of sufficient area to permit the later-to-be-described movement of the pin 294a. The pin 295a extends through apertures in the plates 293 and 294 and the carrier 231 of sufficient area to permit the later-to-be-described movement of the pin 295a. Horizontal pull rods 212, 213 and 214 (Fig. 2) arranged at different elevations extend between the plate 293 and the carrier 231 and each strap at its right end is provided with a horizontal slot on the bottom of which normally rests one of the pins 293a, 294a or 295a, each slot having an upwardly directed opening at its right end to permit upward movement of the pin out of the slot (Fig. 2). Each rod extends a substantial distance to the right beyond the right end of the slot. Leftward movement of any one of the pull rods with the right end of this slot in contact with the pin 293 causes simultaneous vertical movement of such plate through the medium of the pins 296 and resulting movement of the first-mentioned pin upward out of engagement with the rear wall of the slot, thereby freeing the rod for further leftward movement to locate its top edge under the pin to hold the bar in elevated position during further leftward movement thereof.

In the links 161 are provided a pair of apertures 215 and 216 having upwardly directed keyways. Each link is provided with a pin 61a connected to an interlock strap 61. These apertures are adapted to receive pins 217 having keys which will pass through the keyways and then serve to lock the pins in the link (Fig. 3). The end of each pin 217 is bent into radial alignment with the key 217a extending downwardly, thus preventing accidental removal of the pins 217. The pins in the apertures 215 are of sufficient length to extend into the plane of the plate 293 while the pins in the apertures 216 are of sufficient length to extend into the plane of one or both of the plates 294 and 295 (Fig. 1). In curtain-open position, the right edge of carrier 231 engages the arms 160 and is effective upon return of the machine to curtain-open position to restore any actuated arm 160 to the position shown in Fig. 1.

The foregoing mechanism provides means for selectively limiting the number of voting spindles which may be operated in connection with the election of party convention delegates and alternates and other similar election situations. In the election of convention delegates and alternates, members of different political parties are entitled to vote for different numbers of delegates and alternates and it is therefore necessary that of the spindles allocated to the various delegate candidates of the various parties, it be possible for the election officer to limit the number which can be operated by a member of any one of the political parties to a given number, it being customary for the number of delegates and/or alternates to be different for each political party. The mechanism heretofore described constitutes the subject-matter of said

application, Serial No. 260,238, but for the better understanding of the present invention, the operation of such mechanism will be also described herein. For illustrative purposes, assume that the Democratic party elects eight delegates, the Republican party elects four delegates and the Socialist party elects two delegates and that each party has a group of candidates larger than the number of delegates to be elected. Also, assume that the rod 213 is allocated to the Democratic party, the rod 212 to the Republican party and the rod 214 to the Socialist party. The spindle interlock is so adjusted that any eight of the interlock straps 61 connected to spindles allocated to delegate candidates of any party may be actuated but no more than eight. Four pins 217 are inserted in the apertures 215 of four links 161 of sufficient length to extend into the path of the plate 203 (Fig. 1) and six additional pins 217 are inserted in the apertures 216 of six links 161 of sufficient length to extend only into the path of the plate 205. Now further assume that a Republican voter enters the voting booth, whereupon the election officer pulls the rod 212 to effect upward and leftward movement of the plate 203, thus moving the plate 203 from its normal position into the position shown in Fig. 1 to engage the four long pins 217. The plate 203 is moved relative to the plates 204 and 205 on the pins 206 to place it in such position relative to the pins 206 that when the latter are moved to the left by the carrier during curtain closing operation of the machine, the plate 203 will, by engagement therewith of the four long pins 217 to move the attached draw bars 161. Movement of the rod 212 to the left is of such extent as to bring the upper edge of it under the pin 203a to maintain the plate 203 in elevated position during the later-to-be-described leftward movement of the carrier and plates.

Upon movement of the main cam bar 58 into curtain closed position, the bar 63 is elevated and moved to the left, carrying with it the carrier 201 from the position shown in Fig. 1 to a position leftward thereof by a distance equal to the extent of horizontal movement of the bar 63. Such movement of the carrier first takes up the lost motion between the carrier and the pins 206 after which it effects leftward movement of said pins into a position in which the hubs of the washers 210a engage the stop 211a. The plates 203, 204 and 205 are moved correspondingly to the left by reason of the engagement of the pins 206 with the left walls of the plate slots through which the pins extend. There is no corresponding movement of the rods 213 and 214 by reason of the slots in which the pins 204a and 205a slide. The relation of the length of the slots 202 to the extent of horizontal movement of the plate 63 is such that the extent of movement of the plates 203, 204 and 205 equals the extent of movement necessary to draw a wedge 64 between a pair of rollers 62. Therefore, by reason of the engagement of the plate 203 with the four long pins 217, the above-described movement of the plates 203, 204 and 205 with the carrier 201 draws four links 161 to the left with corresponding movement of four wedges 64 between pairs of rollers 62, thereby reducing by four the number of spindles which may be operated by the voter. Upon return movement of the main cam bar to curtain open position, the carrier 201 is returned to the position shown in Fig. 1, and returns any actuated plate 160 and corresponding link 161 to its original position and also returns

the carrier, pins 206 and the three plates to the position shown in Fig. 1. During such return movement, the pins 217 remain in engagement with the left edge of the plate 203 and when the carrier comes to rest they reach the extreme limit of their rightward movement. The plate 203 remains elevated until after the election officer pushes in the rod 212, thus bringing the top opening of the slot in said rod under and the overhanging portion in contact with the pin 203a whereupon the pin is pushed to the right and drops into the slot with corresponding downward and rightward movement of the plate 203 to its original position. Similar operation of the mechanism is effected upon the entry of a Democratic voter or a Socialist voter into the voting booth except that movement of the plate 204 allocated to the Democratic party does not reduce the number of spindles which may be operated by the voter while the operation of the plate 205 allocated to the Socialist party reduces by six the number of spindles which may be operated by the voter.

Each of the arms 160 is provided with a head 160' (Figs. 1 and 8) directed approximately perpendicular to the arm 160. This head projects into a channel-shaped runner 222 (Figs. 1 and 7) slotted at 222a and having a right-angle extension attached to a slide 223 supported by the wall 10 just in back of the guide 224 in which is received the strip on which is printed the names of the various offices to be voted for. Each slide is in alignment with a personal choice slot closure 140. The right edge of the head 160' contacts the shoulder formed by the inner end of the slot 222a so that when the runner 222 is moved to the left from the position shown in Fig. 1, it swings the arm 160 counterclockwise, but the oblique surface 160'' in no way reduces the effectiveness of the tab 160'' in its function of preventing leftward movement of the runner 222 in partisan type voting. The right end of a slide 223 normally engages the left end of a closure 140 so that when a voter moves the latter to the left from the position shown in Fig. 1, it likewise moves the slide to the left. Also leftward movement of a slide 223 effects counterclockwise rotation of the yoke 150 through engagement therewith of the right angle extension by which the runner 222 is connected to the slide 223. The return of the closure 140 to normal position has no effect upon the slide 223. A reinforcing plate 225 is attached to the right angle extension and to the slide 223. Movement of the plate 140 from the slot-closing position shown in Fig. 1 to the left to slot-opening position effects corresponding movement to the left of slide 223 and through engagement of the runner 222 with the head 160' effects swinging movement of the arm 160 counter-clockwise from the position shown in Fig. 1 to actuate the corresponding link 161 and associated interlock strap 61.

Upon operation of one or more links 161 by one of the bars 203, 204 and 205 to determine the number of operable spindles, the arm 160 corresponding to the actuated link has been moved out of locking relationship with respect to the personal choice closure 140 corresponding to each operated link. In order to prevent operation of such closure 140, a depending tab 160'' is provided on an extension from the head 160' and is so located that upon counterclockwise movement of the arm 160 from the position shown in Fig. 1, the tab moves into the path of the runner

222 to prevent substantial movement thereof to the left from the position shown in Fig. 1, such actuated position of the arm 160 being shown in dotted lines. The tab 160'' is provided with an oblique surface 160''' (Fig. 3) facing the runner 222 for the purpose of permitting the machine to be used for general voting.

In Figs. 3 and 4, the upper arm 160 is shown in unactuated position while in Figs. 3 and 5 the second arm 160 is shown as having been actuated by operation of the delegate mechanism to locate the tab 160'' in the path of the runner 222. The second arm 160 is actuated during curtain closing operation of the machine and the tab 160'' is brought into locking relation to the runner 222 before the voter has any opportunity to attempt to actuate a personal choice closure 140 and the size of the tab 160'' is sufficient completely to block movement of the runner 222.

In Figs. 3 and 6, the bottom arm 160 is shown in the position assumed by it when the delegate mechanism is not in use and the personal choice closure has been actuated under general voting conditions. Under such conditions, the pins 217 are omitted so that operation of the carrier has no effect upon the arms 160. As shown in Fig. 3, each arm 160 is supported on the rod 150a in such manner as to be capable of slight tilting movement in a direction normal to the path of swinging movement of the arm. The extent of such tilting movement is sufficient to enable the outer end of the arm 160 to be moved upwardly far enough to have the bottom edge of the tab 160'' lie above the top edge of the lower flange 222' of the runner 222 as is shown in Figs. 3, 5 and 6. Upon leftward movement of the runner 222 by opening of a closure 140, the arm 160 is swung counterclockwise to bring the tab into engagement with the side of the flange 222' of the runner which has moved into the path of the tab and such engagement occurs before the runner has moved leftward sufficient to permit full movement of the closure 140 into slot-open position. The oblique surface 160''' rides up the side of the flange 222' and on to the top thereof thereby permitting full free movement of the runner 222 to its extreme left position. The surface 160''' engages the side of the runner 222 only under conditions of general voting in which circumstance the arm 160 can only be moved by engagement by a runner 222 upon movement of such runner to the left upon actuation of a personal choice closure 140. Under such conditions, the arm and runner move together with the result that the nose of the runner projects leftward beyond the tab 160'', which is not the case when the arm 160 is moved by the delegate mechanism as in such circumstance the arm 160 is moved into operative position before the voter has opportunity to attempt to actuate a personal choice closure 140 as previously described.

Figs. 11 to 17 inclusive disclose a modified means for preventing the opening of a slide 140 corresponding to a link 161 which has been actuated by one of the delegate bars. In this modification, each arm 160 is provided with a substantially arrow-shaped head 160a directed approximately perpendicular to the arm 160 and the reinforcing plate 225 extends above the top edge of the runner 222 to form a shoulder. Associated with each arm 160 is a plate 226 having an offset end 226a in which is provided a socket 226b embracing the rod 150a. The end of the socket 226b is closed by a lever 226 which is

swingable from the position shown in full lines in Fig. 17 to the broken line position shown in the same figure to facilitate mounting the plate on the rod 150a. The plate 226 is arranged directly above each arm 160 and is provided at its under face with a flange 230 having a central recess of slightly greater width than the width of the arm. The plate 226 is held against counterclockwise swinging movement by engagement with the channel member 241 (see application, Ser. No. 260,288) and when the arm 160 is in the position shown in Fig. 11, the right end portion of the flange 230 rests upon the top surface of the arm 160 to maintain the plate 226 in the position shown in Fig. 13. When the arm 160 is swung counterclockwise by a delegate bar, it registers with the cut-out portion in the flange 230 and permits the plate to drop to the position shown in Fig. 14, in which position the end of the plate 226 lies in the path of the left end of the plate 225, thereby locking the runner 222 and also the closure 140 against leftward movement.

When the machine is set up for general voting, and a personal choice closure 140 is actuated, the corresponding arm 160 is actuated through a larger arc than when it is actuated by a delegate bar and the plate 226 is dropped as previously described but not until after the plate 225 has moved under the end of the plate 226 so that the plate 226 does not interfere with movement of the runner 222. It is then lifted to original position by engagement of the arm 160 with the bottom of the flange at the other end of the recess and is held in such position until the arm 160 is returned to original position which is subsequent to the return of the runner 222 to its original position. A spring 160b is provided in each modification to assist in returning the arm 160 to its original position and in the modification illustrated in Fig. 11, a stop 226d is provided to hold the plates 226 against clockwise movement.

Under certain voting regulations, a voter is allowed to record his vote only by writing in a personal choice. In order to condition the arrangement illustrated in Figs. 1 to 8 to meet this regulation, a block 242 (Fig. 9) is provided for attachment to the head 160'. This block is of the same shape as said head and is provided with a pin 243 which fits into a socket 244 in the head and a spring clasp 245 for clamping the block to the head. As shown in Fig. 10, the lower surface of the block is coincident with the tip of the tab 160'' and rides on the bottom of the slot 222a in the runner 222. The tab 160'' is therefore ineffective upon movement of the arm 160 by one of the bars 203, 204 and 205 to lock the runner against leftward movement as previously described. With one or more heads 160' equipped with blocks 242, the corresponding horizontal rows of spindles may be locked out while permitting operation of the corresponding personal choice slot closures 140 after operation of the arms 160 by one of the bars 203, 204 and 205.

It is of course understood that various modifications may be made in the apparatus herein described without in any way departing from the spirit of the invention as defined in the appended claims.

I claim:

1. In a voting machine, a pivoted arm, a voter-actuated slide movable between a first and a second position and effective upon movement from its first to its second position to engage said arm to effect movement thereof in one direction,

a reciprocating carrier normally obstructing movement of said arm in said direction and movable out of obstructing relation and effective upon its return movement to move said arm in the opposite direction, a link connected to said arm, a plate supported by said carrier for movement therewith and for adjustment thereon between two positions, means for effecting adjustment of said plate, means to effect reciprocation of said carrier, a member on said link engageable by said plate upon movement of said carrier out of obstructing relation to said arm with said plate in one position of adjustment on said carrier to swing said arm in said one direction, and means effective upon actuation of said arm by said carrier to lock said slide in its first position.

2. In a voting machine, a pivoted arm, a voter-actuated slide movable between a first and a second position and effective upon movement from its first to its second position to engage said arm to effect movement thereof in one direction, a reciprocating carrier normally obstructing movement of said arm in said direction and movable out of obstructing relation and effective upon its return movement to move said arm in the opposite direction, a link connected to said arm, a plate supported by said carrier for movement therewith and for adjustment thereon between two positions, means for effecting adjustment of said plate, means to effect reciprocation of said carrier, a member on said link engageable by said plate upon movement of said carrier out of obstructing relation to said arm with said plate in one position of adjustment on said carrier to swing said arm in said one direction, and a member supported by said arm in position to be located in the path of said slide upon movement of said arm by said carrier.

3. In a voting machine, a pivoted arm, a voter-actuated slide movable between a first and a second position, a shoulder on said slide engageable upon movement of the slide from its first to its second position with said arm to swing said arm in one direction, a reciprocating carrier normally obstructing movement of said arm in said direction and movable out of obstructing relation and effective upon its return movement to move said arm in the opposite direction, a link connected to said arm, a plate supported by said carrier for movement therewith and for adjustment thereon between two positions, means for effecting adjustment of said plate, means to effect reciprocation of said carrier, a member on said link engageable by said plate upon movement of said carrier out of obstructing relation to said arm with said plate in one position of adjustment on said carrier to swing said arm in said one direction, and means effective upon actuation of said arm by said carrier to lock said slide in its first position.

4. In a voting machine, a pivoted arm, a voter-actuated slide movable between a first and a second position, a shoulder on said slide engageable upon movement of the slide from its first to its second position with said arm to swing said arm in one direction, a reciprocating carrier normally obstructing movement of said arm in said direction and movable out of obstructing relation and effective upon its return movement to move said arm in the opposite direction, a link connected to said arm, a plate supported by said carrier for movement therewith and for adjustment thereon between two positions, means for effecting adjustment of said plate, means to effect reciprocation of said carrier, a member on

said link engageable by said plate upon movement of said carrier out of obstructing relation to said arm with said plate in one position of adjustment on said carrier to swing said arm in said one direction, and a member supported by said arm in position to be located in the path of said slide upon movement of said arm by said carrier.

5. In a voting machine, a pivoted arm swingable between a first and a second position and tilttable in a direction normal to its path of swinging movement, a voter-actuated slide movable between a first and a second position and engageable with said arm upon movement of said slide from its first to its second position to swing said arm in one direction, means independent of said slide for swinging said arm in both directions, a member carried by said arm for movement into the path of a portion of said slide upon movement of said arm by said independent means, and an oblique surface on said member engageable with a side of said slide upon movement of said arm by said slide to tilt said arm in said one direction to locate said member exterior of the path of reciprocation of said slide, and means for directing said member laterally of said path upon movement of said arm by said slide.

6. In a voting machine, a pivoted arm movable between a first and a second position, a slide movable between a first and a second position and effective upon movement from its first to its second position to engage said arm to swing the same in one direction, a reciprocating carrier normally obstructing movement of said arm from its first position and movable out of obstructing relation and effective upon its return movement to swing said arm from its second to its first position, a link connected to said arm, a plate supported by said carrier for movement therewith and for adjustment thereon between two positions, means to effect reciprocation of said carrier, a member on said link engageable by said plate upon movement of said carrier out of obstructing relation to said arm with said plate in one position of adjustment on said carrier, and means effective upon actuation of said arm by said link to lock said slide in its first position.

7. In a voting machine, a pivoted arm movable between a first and a second position, a slide movable between a first and a second position and effective upon movement from its first to its second position to engage said arm to swing the same in one direction, a reciprocating carrier normally obstructing movement of said arm from its first position and movable out of obstructing relation and effective upon its return movement to swing said arm from its second to its first position, a link connected to said arm, a plate supported by said carrier for movement therewith and for adjustment thereon between two positions, means to effect reciprocation of said carrier, a member on said link engageable by said plate upon movement of said carrier out of obstructing relation to said arm with said plate in one position of adjustment on said carrier, and a member supported by said arm in position to be located in the path of said slide upon movement of said arm by said last-named means.

8. In a voting machine, a pivoted arm movable between a first and a second position, a slide movable between a first and a second position, a shoulder on said slide engageable upon movement of the slide from its first to its second position with said arm to swing said arm in one

direction, a reciprocating carrier normally obstructing movement of said arm from its first position and movable out of obstructing relation and effective upon its return movement to swing said arm from its second to its first position, a link connected to said arm, a plate supported by said carrier for movement therewith and for adjustment thereon between two positions, means for effecting such adjustment of said plate, means to effect reciprocation of said carrier, a member on said link engageable by said plate upon movement of said carrier out of obstructing relation to said arm with said plate in one position of adjustment on said carrier, and means effective upon actuation of said arm by said link to lock said slide in its first position.

9. In a voting machine, a pivoted arm movable between a first and a second position, a slide movable between a first and a second position, a shoulder on said slide engageable upon movement of the slide from its first to its second position with said arm to swing said arm in one direction, a reciprocating carrier normally obstructing movement of said arm from its first position and movable out of obstructing relation and effective upon its return movement to swing said arm from its second to its first position, a link connected to said arm, a plate supported by said carrier for movement therewith and for adjustment thereon between two positions, means for effecting such adjustment of said plate, means to effect reciprocation of said carrier, a member on said link engageable by said plate upon movement of said carrier out of obstructing relation to said arm with said plate in one position of adjustment on said carrier, and a member supported by said arm in position to be located in the path of said slide upon movement of said arm by said last-named means.

10. In a voting machine, a pivoted arm movable between a first and a second position, a slide movable between a first and a second position and engageable with said arm upon movement of said slide from its first to its second position to swing said arm in one direction, a reciprocating carrier normally obstructing movement of said arm from its first position and movable out of obstructing relation and effective upon its return movement to swing said arm from its second to its first position, a member movable with said arm into the path of a portion of said slide, a link connected to said arm, a plate supported by said carrier for movement therewith and for adjustment thereon between two positions, means for effecting such adjustment of said plate, means to effect reciprocation of said carrier, means on said link engageable by said plate upon movement of said carrier out of obstructing relation to said arm with said plate in one position of adjustment on said carrier, and means for directing said member laterally of the slide path upon movement of said slide by said last-named means.

11. In a voting machine, a slide movable between a first and a second position and having a shoulder, a pivoted arm engageable by said slide upon movement from its first to its second position to swing said arm into one direction, a plate overlying said arm and supported for vertical movement only, a flange depending from said plate into engagement with said arm to normally maintain said plate out of the path of said shoulder, and means independent of said slide for swinging said arm in said one direction, said flange having a recess of sufficient width to strad-

gle said arm, thereby permitting said plate to fall into the path of said shoulder upon movement of said arm by said independent means.

12. In a voting machine, a slide movable between a first and a second position and having a shoulder, a pivoted arm engageable by said slide upon movement from its first to its second position to swing said arm into one direction, a plate overlying said arm and supported for vertical movement only, a flange depending from said plate into engagement with said arm to normally maintain said plate out of the path of said shoulder, a reciprocating carrier normally obstructing movement of said arm from its first position and movable out of obstructing relation and effective upon its return movement to swing said arm from its second to its first position, a link connected to said arm, a second plate supported by said carrier for movement therewith and for adjustment thereon between two positions, means for effecting such adjustment of said second plate, means to effect reciprocation of said carrier, and a member on said link engageable by said second plate upon movement of said carrier out of obstructing relation to said arm with said second plate in one position of adjustment on said carrier, said flange having a recess of sufficient width to straddle said arm, thereby permitting said first plate to fall into the path of said shoulder upon movement of said arm in said one direction by said carrier.

13. In a voting machine, a pivoted arm, a slide movable between a first and a second position, a first shoulder on said slide engageable upon movement of the slide from its first to its second position with said arm to swing said arm in one direction, a plate overlying said arm and supported for vertical movement only, a second shoulder on said slide, means normally supporting said plate in spaced relation to said arm but effective upon movement of said arm in said one direction to release said plate into the path of said second shoulder, and means independent of said slide for swinging said arm in said one direction to effect movement of said plate into locking relation to said slide.

14. In a voting machine, a pivoted arm, a slide movable between a first and a second position, a first shoulder on said slide engageable upon movement of the slide from its first to its second position with said arm to swing said arm in one direction, a plate overlying said arm and supported for vertical movement only, a second shoulder on said slide, means normally supporting said plate in spaced relation to said arm but effective upon movement of said arm in said one direction to release said plate into the path of said second shoulder, a reciprocating carrier normally obstructing movement of said arm from its first position and movable out of obstructing relation and effective upon its return movement to swing said arm from its second to its first position, a link connected to said arm, a second plate supported by said carrier for movement therewith and for adjustment thereon between two positions, means for effecting such movement of said second plate, means to effect reciprocation of said carrier, and a member on said link engageable by said second plate upon movement of said carrier out of obstructing relation to said arm with said second plate in one position of adjustment on said carrier to swing said arm in said one direction for effecting movement of said plate into the path of said second shoulder.

15. In a voting machine, a pivoted arm swingable between a first and a second position and tiltable in a direction normal to its path of swinging movement, a voter-actuated slide movable between a first and a second position and engageable with said arm upon movement of said slide from its first to its second position to swing said arm in one direction, means independent of said arm in one direction, means independent of said slide for effecting movement of said arm in

said one direction, a member carried by said arm for movement into the path of a portion of said slide upon movement of said arm in said one direction by said independent means, and means for tilting said arm to locate said member laterally of said path upon movement of said arm by said slide.

RANSOM F. SHOUP.
